(57) **CLAIM**

The ornamental design for a digital camera, as shown and described.

DESCRIPTION

FIG. 1 is a front, right and top perspective view of a digital camera, showing my new design;

FIG. 2 is a rear, left and bottom perspective view thereof;

FIG. 3 is a front view thereof;

FIG. 4 is a rear view thereof;

FIG. 5 is a left side view thereof;

FIG. 6 is a right side view thereof;

FIG. 7 is a top plan view thereof;

FIG. 8 is a bottom plan view thereof;

FIG. 9 is a front, right and top perspective view thereof shown in a state of use.

FIG. 10 is a front, right and top perspective view thereof in another state of use.

FIG. 11 is a front, right and top perspective view thereof in another state of use; and,

FIG. 12 is an enlarged view taken from encircled portion labeled, “12,” in FIG. 9.

The broken lines shown in the drawings illustrate portions of the digital camera that form no part of the claimed design. The dot-dash broken lines depict the boundaries of the enlargements that form no part of the claimed design.

1 Claim, 12 Drawing Sheets
